UNITED STATES PATENT OFFICE.

EDWARD J. SMYTHE AND ALEXANDER KERR, OF FAIRBANKS, TERRITORY OF
ALASKA.

DIMMER FOR AUTOMOBILE HEADLIGHTS.

Application filed July 13, 1925. Serial No. 43,349.

The present invention relates to improvements in dimmers for automobile headlights, and its particular object is to provide a dimmer that is very simple, may be easily applied, and is efficient in breaking up and distributing the light rays in such a manner as to prevent the glare of a headlight from blinding pedestrians or drivers of approaching automobiles. Anti-glaring devices have, in the past, been principally incorporated in the lenses which break the rays after the same have been reflected from the usual parabolic reflector surrounding the source of light.

In the present invention it is proposed to provide a dimming device that is immediately associated with the reflector and breaks the light rays while the same are being reflected so as to affect the rays at their source rather than while passing through the lens.

The preferred form of our invention is illustrated in the accompanying drawing, in which

Figure 1 represents a vertical section through a headlight using our dimmer.

Figure 2 a vertical section through the dimmer by itself, and

Figure 3 a front view of the dimmer.

While I have shown only the preferred form of the invention, it should be understood that various changes or modifications may be made within the scope of the claims hereto attached without departing from the spirit of the invention.

In Figure 1 is shown the customary headlight arrangement including a light housing 1, a reflector 2, a lens 3 bearing upon a flange 4 of the reflector and a rim 6 pressing the lens and the flange 4 of the reflector

against the edge of the light housing, with 40 a globe 7 mounted preferably at the focal point of the reflector.

Our dimmer 8 is made of the same form as the reflector so that it may be placed against the active face thereof as shown in 45 Figure 1, and consists of a rather thin sheet of metal perforated as shown at 9 throughout its area, the perforations being comparatively small and being preferably evenly distributed throughout the area of the dim- 50 mer. The latter may be held against the reflector by any suitable means, the same being preferably formed with an axial perforation 11 allowing it to be slipped over the usual cylindrical base 12 of the light, 55 while the rim may be held in place by the lens 3.

In operation the light rays emanating from the source 7 instead of being reflected forwardly in straight lines by the active 60 face of the reflector, are broken up and reflected in numerous, various directions whereby the glare is substantially eliminated.

The dimmer is preferably made of brass 65 or copper.

We claim:

1. The combination of a reflector and a perforated dimmer contacting the active face of the reflector for breaking up light 70 rays striking the same.

2. The combination of a reflector and a perforated dimmer contacting the active face of the reflector for breaking up light rays striking the same, the dimmer being of 75 substantially the same form as the reflector.

EDWARD J. SMYTHE.
